STRAP BUCKLE

Filed April 7, 1927

INVENTOR
Lawrence F. Otten

BY James V. Ramsey

ATTORNEY.

UNITED STATES PATENT OFFICE.

LAWRENCE F. OTTEN, OF FORT THOMAS, KENTUCKY, ASSIGNOR TO THE WADSWORTH WATCH CASE COMPANY, OF DAYTON, KENTUCKY, A CORPORATION OF KENTUCKY.

STRAP BUCKLE.

Application filed April 7, 1927. Serial No. 181,792.

My invention relates to buckles and more particularly to buckles for use upon watch straps.

One object of my invention is to provide simple, convenient, efficient and economical novel means for firmly gripping the free end of the strap and for limiting the movement of the gripping means so that said gripping means cannot be swung into a position which prevents ready functioning thereof.

Another object of my invention is to provide novel gripping means which, when in gripping position, occupy a level below the center of the pivot upon which said gripping means is pivoted and below the top of the buckle frame, thereby giving a more pleasing appearance to the buckle and strap when fastened about the wrist of the wearer.

A still further object of my invention is to provide a buckle adapted for use upon watch straps wherein the buckle may be adjusted at any desired position upon the strap without the danger of slipping so that when the buckle is set in gripping engagement with the strap the user may wear the strap either closely encircling or loose upon the wrist without danger of losing the watch.

The invention consists of a frame of metal having a laterally extending flange on each side which support a stop and removable bar, a cam lever and cam, said removable bar pivotally supporting said cam lever and the looped end of a strap and said cam lever pivotally supporting said cam, which cam wedges the free end of the strap between said cam and the metal frame.

The invention further consists in the construction, combination, location and arrangement of parts as herein set forth and claimed.

In the drawing:

Fig. 1 is a top or plan view of the buckle with the watch strap omitted;

Fig. 2 is a bottom view of the same;

Fig. 3 is a vertical cross-section of the buckle taken on a plane corresponding to line 3—3 of Fig. 1, and showing the ends of the straps by dotted lines and the manner in which the cam wedges the free end of the strap against the buckle frame;

Fig. 4 is a similar vertical cross-section of

the buckle with the strap ends removed and the cam-lever and cam shown in a raised position;

Fig. 5 is an isometric view of the buckle with a portion of the frame broken away, the parts appearing in vertical section taken on a plane corresponding to line 5—5 of Fig. 1, looking in the direction of the arrows;

Fig. 6 is a fragmentary view showing the looped end of the strap which fastens to the buckle;

Fig. 7 is a plan view of the pivoted cam-supporting-lever or arm; and

Fig. 8 is a bottom view of the cam and cam-pivot-bar.

In the embodiment of my invention as illustrated and which shows a preferred construction, I provide a buckle for wrist watch straps comprising frame 1, pivot-pin 2, stop-bar 3, cam-lever 4, cam 5 and cam-pivot-bar 6.

The frame 1 of the buckle consists of laterally projecting side walls 7 and 8 connected at their ends by bars 9 and 10 which may be formed integral with said walls 7 and 8, respectively, as clearly shown in Fig. 5.

Pivot-pin 2 is of the ordinary and well-known construction and is removably mounted between said walls 7 and 8, as by sliding-studs 11 and 12 fitting within holes 13 and 14 in said side walls, respectively.

Stop-bar 3, as shown, is a pin similar to pin 2 and is held between side walls 7 and 8 by sliding-lugs 15 and 16, respectively, fitting within holes 17 and 18 in said side walls. This is the preferred way to provide for stop-bar 3, but it will be understood that a rigid bar fixed between walls 7 and 8 and spaced apart from pivot-pin 2 would be just as satisfactory as there is no need for the removal of stop-bar 3.

The rear or pivoted end of cam-lever 4 is reduced in width and is bent upon itself to form bearing 19, which bearing receives pin 2 upon which it is pivotally mounted, as clearly shown in the figures.

The forward bifurcated end of said cam-lever 4 is bent upon itself to form bearings 20 and 21 which bearings receive and support cam-pivot-bar 6.

Cam-stop 22, integral with the forward

- end of cam-lever 4, is positioned centrally of bearings 20 and 21 and is for the purpose of preventing cam 5 from turning completely around on cam-pivot-bar 6. Cam 5 is provided with a longitudinally extending hole for the purpose of receiving pivot-bar 6 and is provided with recess 24 for the purpose of receiving said cam-stop 22 and has its upper face knurled or roughened, thereby forming teeth 25, which teeth greatly increase the holding power of the cam when wedging the strap between said cam and said bar 10, as will be more clearly described under "Operation".
- 15 One end of the strap, or the end thereof to which the buckle is securely attached, is provided with loop 26, the center of which is cut away at 27, as clearly shown in Fig. 6. The cut-away-portion 27 receives or fits around bearing 19 of cam-lever 4. Cut-away-portion 27 divides loop 26 into separate loops 26^a and 26^b, as clearly shown in Fig. 6, the inner edges 26^c of which bear against the outer edges 19^a of bearing 19 and tends to hold said cam-lever 4 in the center of frame 1, as shown in Figs. 1 and 2.
- 15 Operation.—To engage the strap with the buckle its free end 28 is passed beneath bar 10, which causes cam 5 and cam-lever 4 to swing upwardly on pivot-pin 2, as clearly shown in Fig. 4, so as to allow its free introduction into the buckle. When the free end 28 of the strap is drawn beneath bar 10 to the desired position, simply push down on cam-lever 4 until it limits or is stopped by stop-bar 3, thus making it possible to bring the greater portion of the teeth 25 of said cam 5 below the edge 10^a of bar 10, depending upon the thickness of the strap. The strain or pull of the free end 28 of the strap will cause cam 5 to turn towards edge 10^a of bar 10, thus wedging or clamping the free end of the strap between said edge and said cam, as clearly shown in Fig. 3. As teeth 25 of cam 5 are eccentric with cam-pivot-bar 6, any strain applied to free end 28 of the strap will cause said free end to be wedged tightly between said teeth and edge 10^a of bar 10, as will be clearly apparent by the drawings.
- 50 To unlock or withdraw the free end of the strap from the buckle, simply draw said free end of the strap from beneath bar 9 and draw forward until the cam is turned away from edge 10^a of bar 10; thereby throwing cam-lever 4 and cam 5 out of the locking position, or to a position illustrated in Fig. 4, thus freeing the strap from between the teeth 25 of said cam 5 and edge 10^a of bar 10. The strap may then be readily removed, or the adjustment changed, as desired.
- 55 Upon employing the recess 24 in cam 5, and cam-stop 22 integral with cam lever 4, I prevent the full revolution of the cam upon cam-pivot bar 6, which might otherwise occur, and, if so allowed to revolve would allow the teeth 25 of said cam to drop below cam-pivot-bar 6 which would prevent said cam from operating properly or wedging the strap between itself and edge 10^a of bar 10
- 70
- 75 An advantage of this invention is that when the free end of the strap is passed beneath bar 10 and over teeth 25 of cam 5 and cam-lever 4 is depressed until it limits against stop-bar 3, as shown in Fig. 3, said free end is thus locked between said cam 5 and edge 10^a of bar 10 regardless of whether said free end is passed beneath bar 9.
- 80 Heretofore buckles having cam action for holding the strap would only work provided a strain was maintained on the free end of the strap at all times and under all conditions. With this invention a strap may be worn loosely around the wearer's wrist without the danger of the buckle becoming unfastened due to a diminished strain on the free end 28 of the strap. This feature is accomplished by so arranging cam 5 beneath the center, or to a position below edge 10^a
- 85
- 90 when pressure is applied downward on cam-lever 4. This is made possible due to the flexibility of the material used for straps, as for example leather or fabric, or in other words when downward pressure is applied to cam-lever 4 the teeth 25 of cam 5 are embedded into said strap.
- 95 Another advantage of this invention is that the gripping elements are mounted to occupy a position within the frame, so that when the strap is held in gripped position, it forms a very neat and compact assemblage of the buckle and strap upon the wrist of the wearer and without any uncomfortable inwardly projecting part against the wrist.
- 100
- 105 It will be understood that certain changes and modifications of the invention may be made without departing from the scope or spirit thereof as defined in the claims.
- 110 What I claim as new and desire to secure by Letters Patent is:
1. In a strap buckle, the combination of a buckle frame having laterally projecting side walls, a removable pin supported by said side walls and carrying one end of a strap, a cam lever pivotally mounted upon said pin, a stop for said cam-lever, a cam pivotally mounted upon said cam lever which lever has a stop thereon and which cam is adapted to wedge the free end of a strap between the frame and said cam.
  2. A strap buckle of the character described comprising a frame having laterally projecting side walls, a strap, a cam lever, a removable pin carried by said walls and adapted to have one end of said strap and cam lever pivoted thereto, and a cam carried by said lever for wedging or binding the free end of said strap within said frame.
  3. A strap buckle comprising a frame hav-

ing side walls and a pair of spaced apart pin bars held thereby in combination with a cam lever and cam, said cam pivotally mounted upon said lever and said lever pivotally mounted upon one of said pin bars and abutting against the other of said pin bars.

4. In combination, a buckle frame having an opening therethrough, a lever mounted within said frame and having a cam stop thereon, and a cam pivoted to said lever and having a recess therein adapted to receive said cam stop, for the purposes specified.

LAWRENCE F. OTTEN.
